[57] **CLAIM**

The ornamental design for a newspaper vending bin or similar article, as shown and described.

DESCRIPTION

FIG. 1 is a perspective view taken from the top, front and left side of a newspaper vending bin or similar article showing my new design;

FIG. 2 is an exploded perspective view taken from the top, front and left side thereof;

FIG. 3 is a perspective view taken from the top, rear and left side thereof, showing the display header in a raised position; and

FIG. 4 is a perspective view taken from the bottom, front and right side of the bin portion thereof with the display header and inside rear panel of the bin omitted for ease of illustration.

The broken line showing of areas for indicia in FIGS. 1 and 2 are for purposes of illustration only and form no part of the claimed design.

FIG. 1FIG. 2FIG. 4FIG. 3
